JOSEPH A. CEREGHINO, OF LOS ANGELES, CALIFORNIA, ASSIGNOR TO NATIONAL LABELING MACHINE COMPANY, OF LOS ANGELES, CALIFORNIA, A CORPORATION OF CALIFORNIA.

METHOD OF AND APPARATUS FOR PASTING LABELS ON NONCIRCULAR CANS AND CONTAINERS.

Application filed August 13, 1923. Serial No. 657,057.

This invention relates to machines for pasting labels on containers.

Label-pasting machines heretofore in use are applicable only to circular cans or containers which may be rolled easily when their axes are disposed horizontally. This invention is designed to provide a machine which will apply or affix labels to non-circular cans and containers, such as oval, 10 square or rectangular cans which are used quite generally in the packing of fruits, vegetables and fish. Hitherto in practice these non-circular cans and particularly oval cans have been labeled by hand, the cost 15 being about 4¢ per case. With the machine of the present invention this work can be done at one-half the cost.

A principal object of the invention, therefore, resides in providing a label affixing 20 machine for operating on irregular contour cans and containers, wherein is provided means for automatically receiving containers successively from a suitable source of supply; continuously moving said containers in 25 such processional arrangement that each container and a label are so prepared and brought into such operative relation that the label is caused to be wrapped around the container and become affixed thereto.

Another object of the invention resides 30 in providing paste applying devices of a peculiar and special construction and arrangement, whereby the movements of a container adjacent said paste applying devices will so effect their operation and action as 35 to cause a predetermined area of each can or container to receive a measured application of paste, whereby as the container advances in its path of movement it automatically engages and extracts a label from 40 a suitable source of supply and winds said label around its periphery.

Other objects and advantages than herein 45 enumerated have been evolved in the designing of a machine embodying my invention, and I consider all such advantages as fall within the scope and meaning of the claims hereto appended as coming within the purview of my invention. I also wish it understood that the several necessary elements, 50 parts and combinations constituting the same may be varied in their proportions, placement and general arrangement with-

out departing from the scope and nature of the invention. 55

In connection with the drawings forming a part of this application, I wish to point out that the general arrangement of the related operative parts, their placement and operative timing have all been so shown 60 and displayed that the operation of the invention would be most clearly understood. The drawings, therefore, are to be looked upon as somewhat diagrammatic in character and disclosure and not necessarily representing manufacturing procedure. 65

The machine in its preferred form includes conveyer mechanism, carrying a plurality of chucks rotatably mounted thereon on vertical axes to receive the cans or containers in upright position. At one side of the conveyer are paste-applying devices and at the other side is a magazine for holding labels. As the cans are carried along by the conveyer they are rotated on a vertical 70 axis and come in contact with the paste-applying devices and the labels whereby paste will first be applied at desired points on the can body and thereafter the label will be engaged so as to adhere to the can body 75 and be carried around as the latter rotates.

One form which my invention may assume is exemplified in the following description and illustrated in the accompanying drawings, in which— 80

Fig. 1 is a side elevation of a machine embodying my invention and clearly shows the endless conveyer carrying the can chucks; the power means for driving the various moving elements and the drive connections for operating the paste-applying devices. 85

Fig. 2 is a plan of Fig. 1 with the various parts and elements in approximately the same related positions as Fig. 1, except that the delivery chute end and parts of the spring pressed top rail for holding the cans on the chucks has been broken away. 90

Fig. 3 is a vertical, transverse, sectional elevation taken on approximately the line 3—3 of Fig. 2 but made on an enlarged scale to more clearly show the relations of the parts displayed, this view clearly showing the relation of the label magazine and paste-applying devices with the can-holding chucks and the top presser bar for holding 100 105

the cans down on the chucks and the cans having been omitted in this view to more clearly show the relation of the various operative elements.

5 Fig. 4 is a diagrammatic view illustrating the lineal and rotative paths of an oval can, such as this machine is equipped to operate upon, and illustrates the manner in which the ends only of the oval can are successively supplied with paste. In this view I have placed a small cross on the same end of the can so its path of movement is more easily followed.

10 Fig. 5 is a diagrammatic view similar to Fig. 4 but illustrating the movements of a square can in relation to the paste-applying devices.

15 Fig. 6 is a longitudinal, sectional elevation, taken on approximately line 6-6 of Fig. 2 but on an enlarged scale and showing only the top portion of the machine. In this view is clearly shown the manner in which the chucks automatically take the cans from the delivery chute; how the can rests on the chuck as it is conveyed through the machine and its relation to the paste-applying devices. This view also shows a sectional elevation of the paste box and contiguous parts at a right angle to that of Fig. 3, and also clearly shows the location of the pivot on which the paste boxes swing during their operative movement.

20 Fig. 7 is an enlarged detail of the paste box and the paste-applying devices, taken through the groove of a paste wheel showing how the concave faced paste wheel will deliver paste successively to each of several transfer grooves that are superposed one above the other; that are of equal diameter and that are positioned at varying distances from the periphery of the paste wheel.

25 Fig. 8 is an enlarged view of the oval end of a can, showing the four lines of paste as applied by the transfer grooves of the paste-applying device.

30 Fig. 9 shows a plan view of the discharge end of the delivery chute, illustrating the stop blocks for positioning the cans where they will be engaged by the chucks.

35 Fig. 10 shows a plan view of one of the chucks.

40 Referring in detail to the accompanying drawings, it will be seen that the machine comprises a frame 10, at each end of which is a sprocket wheel 11, and running over the sprocket wheels is an endless chain 12. Secured to this chain at suitable intervals are chucks 13 turnable on vertical axes 14, and each carrying a toothed gear 15 at its side. The chuck proper is somewhat oblong, being of greater length than the diameter of the gear but of less width. These chucks, during their travel along the bottom run of the conveyor and at the beginning and end of the upper run, are disposed with their

major axes extending longitudinally of the conveyer and are held against turning movement by having straight sides in engagement with guide rails 16.

45 Cans 17 are fed on to the chucks through an inclined chute 18, with the major axis of the can disposed in the direction of travel of the conveyer. The bottom of the can contains a depression 19 resulting from the formation of a seam at the rim thereof, such depression being non-circular as is the can body. The chuck is of such size as to fit this depression in the direction of its major axis so as to cause turning of the can when the chuck is turned, at the same time permitting the can to project beyond the sides of the chuck in the direction of the minor axis. The cans are held seated upon the chucks by a spring-pressed rail 20 at the top thereof.

50 Immediately after the can is seated on the chuck, the gear on the latter comes into mesh with a toothed rack 21, causing the chuck to turn and carrying the can around. At desired intervals on one side of the conveyer I arrange a plurality of adhesive-applying devices, each comprising a vertical shaft 22 formed with circumferential corrugations 23. A concave roller or disk 24 on a horizontal shaft 25 is positioned in a pan or pot 26 and contacts with the corrugations on the vertical shaft 22. The pan or pot contains paste and this paste is carried by the roller or disk 24 and applied to the corrugated shaft 22, which, in turn, contacts with the can body and deposits paste or glue thereon at the desired points. The horizontal shaft 25 is driven by a chain 27 and the vertical shaft 22 is driven by bevel gearing 28 and a counter shaft 29, the latter being operatively connected with the horizontal shaft 25.

55 In this manner the corrugations on the vertical shafts 22 are kept supplied with paste or glue and the side walls of the can remotest from the center of the chuck will come in contact with these corrugated shafts as the can moves past. The first paste applying device is positioned to contact with an oval can near the middle of one of its short sides, as shown in the diagram of Fig.

60 4. In the case of a square can the first paste-applying device will contact with one of the corners of the can, as shown in Fig. 5. This pasted corner of a square can or the short curved section of an oval can will continue around, as indicated in dotted lines, to the opposite side of the conveyer where it comes in contact with the end of a label 26^a. A quantity of labels are arranged in a magazine 27^a and extend lengthwise alongside of the conveyer and are pressed towards the front of the magazine by a follower block 28' which is moved forwardly through counterweights 29'. The front of the maga-

zine is open and the labels are kept in place by pins 30 arranged at the top and bottom at suitable intervals. As the pasted surface of the can contacts with the end of the label 5 the latter will be pulled out of the magazine, being punctured slightly at its top and bottom to release itself from the pins 30. Meantime the other corner or short curved section of the can is being pasted by intermediate pasting devices, so that when the latter portion of the can comes in contact with the label the latter will adhere thereto. Finally the corner or curved section originally pasted will again contact with a pasting device and the front end of the label, together with the adjacent surface of the can, will receive additional paste or glue 10 so that the overlapping ends of the label will be pasted together and to the can. 15 When dealing with oval cans I prefer to use three pasting devices so positioned as to apply paste first to one short curved section, then to the opposite short curved section and finally to the first-mentioned curved section. Thereby the label is pasted at its overlapping ends and at its middle. When dealing with square or rectangular cans I 20 may use three or five paste-applying devices. When five are employed, each corner of a can will be pasted and the first corner repasted to secure the overlapping ends of the label in place. 25

A label smoothing member 31 is arranged in the path of the rotating can in position 30 to press against the overlapping ends of the label and thus assist in sealing the ends in place and smoothing out any wrinkles formed in the label. By the time a can nears the end of the conveyer it has made 35 two and one-half revolutions and the chucks are again disposed with their major axes extending longitudinally of the conveyer. At this point the toothed rack terminates and the chuck passes between inclined rails 40 32 which project up above the adjacent sides of the chuck and act to lift the can off and deliver it by gravity or otherwise to the desired point. The chuck continues along the bottom run of the conveyer, being held 45 against turning movement by contact with the guide rails 16.

A feature of the paste-applying devices consists in connecting each box or pan on a vertical pivot 33 at the side opposite the vertical shaft 22 and arranging a spring-pressed plunger 34 at one corner of the pan 50 to force the pan inwardly toward the conveyer whereby the paste-applying shaft will press yieldingly against the side or corner 55 of the can.

The problem involved in mechanically pasting labels on cans or packages of non-circular configuration is one of avoiding slack in the label. Inasmuch as the can is 60 irregular in shape it is not at all times in

contact with the label during its turning movement as is a circular can, and hence if its rotative and linear movements are not properly related, slack will occur in the label between the points of adhesion. The 70 desired result is obtained by using a gear having a circumferential pitch equal to the perimeter of the can body. In this way the same effect is obtained as if the can were circular and remained in contact at all times 75 with the label while being rolled or rotated.

As a means of feeding the cans so as to position them properly on the chucks without resorting to timing mechanism I make use of a delivery chute formed of spaced 80 angle bars of resilient material. At the discharge end of these bars are arranged stop lugs 35 which arrest the downward movement of the cans. The short curved section of the can, however, projects beyond 85 the delivery chute and into close proximity with the conveyer so that when a chuck approaches it engages the rim of the can and pulls the latter off the delivery chute, the angle bars spreading apart to allow the can 90 to pass between the lugs.

The operation of my improved non-circular, can-labeling machine is as follows: Suitable adhesive is placed in the paste boxes 26 and a pack of labels placed in the 95 label magazine 27. Cans are started down the chute 18, where they slide instead of roll, and are retained in position for feeding therefrom by means of the stop blocks 35. Power is provided to operate the machine through the medium of a motor and suitable reduction gearing clearly shown in side elevation in Fig. 1. Electric switch and controlling means may be located at any suitable place; these have not been illustrated as they are procurable through ordinary commercial channels. The motor being started, the conveyer chain carrying the chuck members begins to advance under the chute containing the cans, and as the forward edge of a chuck approaches the downwardly inclined edge of the foremost can in the chute, it engages the seam edge of this can, as is shown in Fig. 6, and by its advancing movement pulls the can out of the 110 chute against the resistance of the spring pressed retaining block 35, the spring action of this block resulting from the thin steel bar carrying the block, and, as the can and chuck advance together the can gradually 115 lowers onto the chuck and is finally forced into position thereon through the action of the spring pressed top bar 20 extending longitudinally over the path of the cans. As soon as each chuck reaches the longitudinal 120 rack 21 the teeth of the chuck gear engage with the teeth of the rack and the chuck begins axial rotative movement. The drawings illustrate a machine as adjusted and equipped to handle and label oblong cans. 125

The commencement of rotation of each chuck as it engages the rack is so timed in relation to the first paste box and the paste applying devices that one end of the oval can will contact with the corrugated paste transfer roll and receive several parallel lines of paste as it moves along in contact with said roll.

The positioning of the paste box is such that the corrugated rolls intersect the path of movement of the ends of the oval cans, so that in order for the ends of the cans to pass they must swing the paste box and all of its mechanism about the pivot 33 against the restraining action of the spring pressed plunger 34, which plunger 34 will immediately return the paste box to its normal position. This swinging action permits the corrugated paste transfer rolls to roll over the oval end of the can and thereby transfer the several lines of paste around this oval end as has been referred to.

The continued lineal and rotative movement of the can will carry this pasted end around its axis until it comes in contact with the end of the outermost label of the pack on the opposite side of the path of travel. The paste being somewhat quick drying and having very strong adhesive qualities will immediately pick up the end of the label, and, as the rotation of the can continues will begin to wind the label around its outer surface between the top and bottom seams.

At about the same time that the first pasted oval end of the can picks up the end of the label, the other oval end of the can approaches and comes in contact with the corrugated paste transfer rolls of another past-applying device and gathers a supply of adhesive in the same manner as has been described for the first end. The application of paste to this oval end of the can is to secure the label at a point near its center as it is wound about the can and thereby help to keep up any slack or slippage that may occur through loosening of the label as it is drawn from the face of the pack of labels.

The continued lineal and rotative movement of the chuck and can continues to wind the label around the can, and, as the first pasted end of the can completes a half revolution after picking up the label, this end and the adhering end of the label are treated to another application of paste by coming into the operative zone of another paste-applying device wherein part of the applied paste goes on the end of the label and the balance on the surface of the can. Further continued lineal and rotative movement of the can completes the winding of the label around the can and overlaps the ends of the label just as it is finally pulled away from the pack of labels. The can now continues its rotative and lineal movement and just as it reaches the end of another half revolu-

tion the overlapped ends of the label come into contact with the yielding label smoothing and wiping member 31 which acts to firmly press the label to the can and smooth out any possible wrinkling or unevenness that may have occurred in the winding of the label about the can.

On account of the gear on each chuck having a pitch circumference equal to the peripheral circumference of the can being operated upon, there should normally be no wrinkling or slack in the label as it is applied. Labels, however, are made of paper which is a very absorptive material and they are more or less affected from day to day by the ordinary changes of humidity in the atmosphere.

Labels for the ordinary oval can are a matter of sixteen inches long and it is not at all unusual for them to vary from a sixteenth to an eighth of an inch in length between very dry days and very moist days. This difference in length from day to day is immaterial as far as covering the can is concerned, but may affect the operation of wrapping the label smoothly around the can. It, therefore, may so proportion the rotative to the lineal speed of the can so that a slight pull of the label will be effected as it is wound around the can. This may help materially in having the label lie smoothly without wrinkles or slackness, so that the final action of the smoothing and wiping member 31 would simply be to cause the overlapping ends of the label to lie flat and in cemented contact.

Of course, it is understood that all surfaces of the oval can will not have the same circumferential speed, but it is the oval ends of the can that really carry the label away from the pack and if the speed of these ends is sufficient to create a slight pull on the label it will wind much smoother than by a simple wrapping movement.

Each can and label pass through the same sequence of movements as has just been described, so that a continuous supply of cans will permit of a continuous labeling operation and thus give high operative capacity to a feature of can labeling that has heretofore been a slow laborious hand operation.

The exact manner of applying the paste from the main paste-carrying roll to the grooved transfer roll is worthy of a little description. By reference to Fig. 7 the relative location of the transfer roll to the main roll will be seen. It will be observed that the grooves of the transfer roll occupy positions of varying distance from the paste-carrying surface of the main paste roll; the uppermost groove lying farthest away from the concave surface or face of this roll. As the main roll rotates in the body of paste in the box 26 the paste adheres to the surface thereof and is carried up and around,

as is indicated by the numeral 36, and as the upper groove of the transfer roll is farthest away from the surface of the paste roll the outermost peripheral surface of the paste 5 will be picked up by this groove as the wheel rotates. The next groove lying a little closer to the face of the paste wheel will receive its supply of paste from the new peripheral surface of the paste created by the removal 10 of paste by the first groove. This operation is successively repeated for each groove as the paste wheel rotates until each groove has received a supply, and, owing to the continuous rotation of the paste wheel 24 15 and the grooved transfer wheel 23 a continuous supply of paste is given to the grooves of the transfer wheel to replace that transferred to the surfaces of passing cans.

The fluid consistency of the paste and the 20 peripheral speed of the large paste roll will have some measure of influence in determining the amount of paste that is carried around for distribution to the grooves of the transfer roll. This will also be influenced somewhat by the depth of immersion of the large 25 paste roll in the body of paste. These various conditions are amenable to manipulation so that practically any condition of operation of the paste applying devices 30 may be established to suit any conditions of operation of the machine as a whole and to suit varying shapes and sizes of cans that may be operated upon.

Having thus described my invention, what 35 I claim and desire to secure by Letters Patent is:

1. A method of pasting labels on non-circular packages comprising the steps of advancing the package bodily and simultaneously 40 rotating the same, applying adhesive material to the body of the package at points remotest from the center thereof and bringing such points into contact with a label while one end of the latter is held stationary to produce a slight tension 45 thereon and so timing the movement of the package that it will be advanced a distance corresponding to the length of its perimeter during one revolution and wrap the label 50 about itself by reason of said tension.

2. A method of applying a label to a package of non-circular configuration which consists of advancing the package bodily and simultaneously rotating the same through a 55 course which will bring the points remotest from the center of the package into contact with a label while one end of the latter is held stationary to produce a slight tension thereon, the movement being such that the package will progress a distance corresponding to the length of its perimeter during one revolution and wrap the label about itself by reason of said tension.

3. A method of applying a label to a 60 package of non-circular configuration which

consists of advancing the package bodily and simultaneously rotating the same through a course which will bring the points remotest from the center of the package into contact first with adhesive applying devices and then 70 with a label while one end of the latter is held stationary to produce a slight tension thereon, the movement being such that the package will progress a distance corresponding to the length of its perimeter during 75 one revolution and wrap the label about itself by reason of said tension.

4. A method of applying labels to packages of non-circular configuration consisting of advancing the package along a horizontal 80 path while simultaneously rotating it about a vertical axis, disposing along the path of travel of the package in successive order adhesive-applying devices and labels so positioned that the points of the package remotest from the center will contact therewith. 85

5. A method of applying labels to packages of non-circular configuration consisting of advancing the packages and simultaneously 90 rotating them, applying adhesive to the first promontory on the package, bringing that promontory into contact with one end of a label, applying adhesive to the next promontory on the package and bringing it into contact with an intermediate portion of the label and finally applying adhesive to the first-mentioned promontory and bringing it into contact with the other end of the label, the last-named end of the label 95 being meanwhile held stationary. 100

6. A method of applying labels to packages of non-circular configuration consisting of advancing the packages and simultaneously 105 rotating them, applying adhesive to the first promontory on the package, bringing that promontory into contact with one end of a label, applying adhesive to the next promontory on the package and bringing it into contact with an intermediate portion of the label and finally applying adhesive to the first-mentioned promontory and bringing it into contact with the other end of the label and timing the advancement and rotation of the package so that but one revolution 110 will occur during the distance of travel corresponding to the length of the perimeter of the package. 115

7. A machine for applying labels to packages of non-circular configuration comprising means for advancing the packages along a horizontal path, means for simultaneously rotating the said packages about a vertical axis and adhesive-applying devices and labels disposed along the line of travel of the packages in successive order and so positioned that the promontories on the packages will contact therewith. 120 125

8. A machine for applying labels to packages of non-circular configuration comprising 130

- ing means for advancing the packages along a horizontal path, means for simultaneously rotating the same about a vertical axis, said advancing and rotating means being so timed that the packages will be turned one revolution during a distance of travel corresponding to the length of the perimeter of the package, and means for disposing labels in extended position in the path of movement of the packages and disposed parallel thereto.
9. A machine for applying labels to packages of non-circular configuration including means to support the package for rotation on a vertical axis and means to effect said rotation comprising a gear whose pitch circumference is equal to the perimeter of the package to be labeled, and means for disposing labels in extended position in the path of movement of the packages and disposed in uniform spaced relation to the path of travel of the rotating axis of the package.
10. In a machine for applying labels to non-circular packages, a traveling chuck to support the package for rotation on a vertical axis, a gear on the chuck and a toothed rack to engage the gear for turning the chuck, the pitch circumference of the said gear being equal to the perimeter of the package to be labeled, and means for disposing labels in extended position in the path of movement of the packages and disposed in uniform spaced relation to the path of travel of the rotating axis of the package.
11. In a label-pasting machine for cans, the combination with an inclined delivery chute having yielding means at its end to arrest the can in position where the rim of its bottom will overhang, of a traveling chuck positioned to engage the overhanging rim and pull the can off the delivery chute.
12. In a label-pasting machine for cans, the combination with an inclined delivery chute formed with side rails of spring material and having stop lugs at their end to arrest the can in position where the rim of its bottom will overhang, of a traveling chuck positioned to engage the overhanging rim and pull the can off the delivery chute.
13. In a label-pasting machine for cans, the combination with a travelling chuck to receive a can, and of less width than the can, to allow the can bottom to project beyond at each side, of delivery means at each side of the chuck to engage the projecting portions of the can bottom and lift it from the chuck.
14. In a label-pasting machine for cans, the combination with a traveling chuck to receive a can, and of less width than the can, to allow the can and bottom to project beyond at each side, of delivery means including an inclined track at each side of the chuck, to engage the bottom of the can and lift it from the chuck.
15. In a label-pasting machine, the combination with a conveyer for advancing and simultaneously rotating a package to be labeled of an adhesive-applying device comprising a vertically disposed rotary shaft formed with circumferential rings or corrugations to contact with the rotating package, a paste receptacle, and means for transferring paste from the receptacle to the adhesive-applying device.
16. In a label-pasting machine, the combination with a conveyer for advancing and simultaneously rotating a package to be labeled, of an adhesive-applying device comprising a pan or container for adhesive, spring means for permitting movement of the adhesive-applying device towards and from the conveyer and a rotary paste-applying element mounted on the pan and disposed in position to contact with the package to be labeled.
17. In a label-pasting machine, the combination with an endless conveyer of a chuck mounted thereon for rotation about a vertical axis, a gear encircling the chuck, said chuck having its top portion of oblong shape with straight sides at right angles to its minor axis, guide rails to contact with said straight sides throughout a portion of the travel of the conveyer whereby to maintain the chuck in stationary position with its major axis extending longitudinally of the conveyer and a toothed rack to engage the gear on the chuck to rotate the same during the remainder of the travel of the conveyer.
18. In a machine for applying labels to cans of non-circular configuration, an endless conveyer, a chuck mounted thereon for rotation about a vertical axis, said chuck being oblong in outline and being of a length sufficient to fit the greatest length of the can bottom whereby to prevent relative movement between the chuck and the can and a spring-pressed bar above the conveyer with which the can top contacts for maintaining the can seated upon the chuck.
19. The method of applying coverings to articles of manufacture comprising the positive moving of articles through both rotative and lineal paths, applying adhesive at predetermined points in their paths of travel, disposing labels with their ends and intermediate portions in the path of travel of the articles, bringing the adhesive portions of said articles into contact with labels, whereby said labels will be wrapped about said articles and be affixed thereto.
20. The method of applying and affixing labels to the perimeters of articles of manufacture, comprising the positive moving of articles, simultaneously, through both rotary and lineal paths, disposing labels with their ends and intermediate portions in the path of travel of the articles, applying adhesive to portions of each article in predetermined periods, bringing an adhesive portion of each article into contact with a label, whereby

said label is caused to adhere to said article and be wrapped therearound and affixed thereto.

21. The method of applying labels to non-circular containers, comprising the moving of containers, successively, in predetermined lineal paths and in processional arrangement, imparting predetermined rotative movement to said containers as they are moved lineally, disposing labels with their ends and intermediate portions in the path of travel of the articles, applying adhesive to portions of each container as it passes adhesive-applying stations, successively bringing each container into contact with a label whereby the rotation of said container will pick up and wrap the said label about its perimeter and overlap the ends thereof.

22. A method of affixing labels to containers, comprising the positive moving of containers in processional arrangement, simultaneously giving each container lineal and rotative movement, applying adhesive to a portion of each container, contacting said adhesive portion with a label whereby said label is caused to adhere to said container and be wrapped thereabout as said container is rotated, applying adhesive to another portion of said container, continuing the rotation and wrapping of said label around said container, again applying adhesive to a portion of the area that first received adhesive, and to the outer surface of the end of the label adhering to the said container and continuing the rotation of said container, whereby the said label is completely wrapped thereabout and the ends overlapped and secured together.

23. A machine for automatically applying labels to containers, comprising means for positively holding and moving containers in both linear and rotary paths, means located within the rotary paths of said containers for applying adhesive thereto, labels located with their opposite ends within the rotary and linear paths of said containers for contacting therewith and becoming affixed thereto.

24. A machine for automatically applying labels to containers, comprising means for extracting containers from a suitable source of supply and imparting rotary movement to said containers, means for imparting linear movements to said containers, rotary dispensing devices for applying paste to said containers, and means for causing a label to adhere to each container as it passes along its path and become affixed thereto.

25. A machine for automatically applying labels to containers, comprising means for extracting containers from a suitable source of supply and imparting rotary movement thereto, means for imparting linear movement to said containers, paste-dispensing devices for applying paste to said containers

and having both rotary and swinging movement, and means for causing a label to adhere to each container as it passes along its path and become attached thereto.

26. An apparatus for applying paste to the surfaces of containers for the attachment of labels thereto, comprising two rotary elements having their axes of rotation disposed at right angles, one of said elements having paste transfer grooves and the other of said elements having a concave face and adapted to carry paste from a suitable source of supply and deposit portions of same in the said transfer grooves.

27. An apparatus for applying paste to the surfaces of containers for the attachment of labels thereto, comprising paste-dispensing means mounted for rotary movement, a receptacle for containing a body of paste and adapted to support said paste-dispensing means, said paste-dispensing means comprising a carrying member, and a transfer member, said carrying and transferring members being mounted for rotation on axes at right angles to each other, and means for imparting simultaneous rotation to said members whereby paste is transferred from one of said members to the other of said members.

28. An apparatus for applying paste to the surfaces of containers for the attachment of labels thereto, comprising rotary elements mounted for rotation and disposed in operative relation thereto, one of said elements being a carrying member and the other of said elements being a transfer member and adapted to receive paste from the carrying member, a receptacle for containing a body of paste and having means for supporting said rotary paste-applying elements, the whole comprising a complete unit, and means permitting said receptacle to swing from its normal location during certain periods of operation.

29. An apparatus for applying paste to the surfaces of containers for the attachment of labels thereto, comprising rotary elements having their axes of rotation disposed at differing angles, one of said elements having transfer grooves and the other of said elements having a concave face and adapted to carry paste from a suitable source of supply and deposit the same into the said transfer grooves, said rotary paste elements being mounted for swinging motion as well as for rotary motion.

30. A method of applying a label to the package of non-circular formation, which consists of disposing the label in a straight line and temporarily holding one of its ends, thereafter advancing the package bodily while simultaneously rotating the same on its central axis, the path of travel of said central axis being uniformly spaced from and parallel to the label, the distance between said label and the path of travel of

the rotating axis of the package being equal to the radial length of the promontories of the package from said axis, whereby only the promontories of the package will contact with the label as the package advances and rotates.

31. A method of applying labels to packages, which consists in disposing the label lengthwise and temporarily holding one end thereof, thereafter advancing and simultaneously rotating the package along a path of travel parallel to the label and in a direction from the free end to the held end of the label, and applying an adhesive to a spot on the package prior to its contact with the label and to other spots on the package during the label-wrapping operation, whereby the label will be fastened to the package.

32. A method of applying labels to non-circular packages which consists in disposing the label lengthwise and holding one end thereof, thereafter advancing and simultaneously rotating the package along a path of travel parallel to the label and in a direction from the free end to the held end of the label, and consecutively applying an adhesive to the promontories of the package as said package advances and rotates, whereby the label will be wrapped around and caused to adhere to the package during its advance.

33. A method of applying labels to non-circular packages, which consists in disposing the label lengthwise and temporarily holding one end thereof, thereafter advancing and simultaneously rotating the package along a path of travel parallel to the label and in a direction from the free end to the held end of the label, whereby the promontories of the package will successively contact with the label, then applying adhesive to the promontories as they advance into contact with the label, said operation taking place while the package advances and rotates at a rate of speed which will cause the portion of label between a point to which the label has adhered and a point in contact with the label, to be drawn taut as the package advances.

34. A machine for applying labels to packages, comprising means for supporting labels in a straight line, a series of adhesive-applying means arranged in a line parallel to said label and spaced therefrom, and means for advancing and simultaneously rotating a package along a parallel path of travel between the adhesive means and the label, whereby points on the package will be consecutively supplied with adhesive as the package rotates and will be brought into contact with the label.
